(57) CLAIM

We claim the ornamental design for a drain cover, as shown and described.

DESCRIPTION

FIG. 1 is a top perspective view;

FIG. 2 is a bottom perspective view;

FIG. 3 is a top plan view;

FIG. 4 is a bottom plan view;

FIG. 5 is a front elevation view;

FIG. 6 is a cross-sectional view taken from line 6-6 of FIG. 3; and,

FIG. 7 is a cross-sectional view taken from line 7-7 of FIG. 3.

Wherein the right, left and rear elevations are identical to the front elevation.

The broken lines shown in the drawings illustrate portions of the drain cover that form no part of the claim.
